CLAIM

We claim the ornamental design for a shower handle assembly, as shown and described.

DESCRIPTION

FIG. 1 is a perspective view of an embodiment of the claimed design;

FIG. 2 is a front elevation view thereof;

FIG. 3 is a rear elevation view thereof;

FIG. 4 is a view thereof from the first direction;

FIG. 5 is a view thereof from the second direction;

FIG. 6 is a view thereof from the third direction; and,

FIG. 7 is a view thereof from the fourth direction.

The ornamental design which is claimed is shown in solid lines in the drawings. The broken lines in the drawings are for illustrative purposes only and form no part of the claimed design. Broken lines formed by equal length dashes show unclaimed subject matter. Broken lines formed by unequal length dashes (i.e., dash-dot) define bounds of the claimed design. Broken away symbols having a jagged element show that no particular length of the portion is claimed. The appearance of any portion of the article between the broken symbols forms no part of the claimed design.
